(57) **CLAIM**

The ornamental design for a display screen with an animated graphical user interface, as shown and described.

DESCRIPTION

FIG. 1 is a front view of a first image in a sequence of a display screen with an animated graphical user interface, showing our new design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof;

FIG. 8 is an eight image thereof;

FIG. 9 is a ninth image thereof; and,

FIG. 10 is a tenth image thereof.

The appearance of the transitional image sequentially transitions between the images shown in FIGS. 1 through 10. The process or period in which one image transitions to another image forms no part of the claimed design.

The inner broken-line rectangle illustrates the perimeter of the display screen. The outer broken-line rectangle illustrates an electronic device. The remaining broken lines, including all text, illustrate portions of the graphical user interface. The broken lines form no part of the claimed design.
